UNITED STATES PATENT OFFICE

110,225

DESIGN FOR A PLAY BALL GOAL

William A. Schutt, Litchfield, Ill.

Application April 13, 1937, Serial No. 68,735

Term of patent 7 years

To all whom it may concern:

Be it known that I, William A. Schutt, a citizen of the United States and a resident of the city of Litchfield, county of Montgomery and State of Illinois, have invented a new, original, and ornamental Design for a Play Ball Goal, of which the following is the specification, and reference being had to the accompanying drawing, forming a part thereof.

The figure is a perspective view of a play ball goal showing my new design.

I claim:

The ornamental design for a play ball goal, as shown.

WILLIAM A. SCHUTT.
